(57) **CLAIM**

The ornamental design for a drink and food tray, as shown and described.

DESCRIPTION

FIG. 1 is a front perspective view of a drink and food tray showing my new design;

FIG. 2 is a top view thereof;

FIG. 3 is a side view thereof, the opposite side being a mirror image thereof;

FIG. 4 is a front view thereof, the rear view being a mirror image thereof; and,

FIG. 5 is a bottom view thereof.

The circular broken lines shown in FIGS. 1 and 2 represent fold lines.

1 Claim, 5 Drawing Sheets*FIG. 1*

FIG. 2

FIG. 3

FIG. 4

FIG. 5
